(57) **CLAIM**

The ornamental design for a computer workstation, as shown and described.

DESCRIPTION

FIG. 1 is an isometric view from the front showing the front, left and top sides of a preferred embodiment of our design. FIG. 2 is an elevation view from the front showing the front side of a preferred embodiment of our design.

FIG. 3 is an elevation view from the left showing the left side of a preferred embodiment of our design.

FIG. 4 is an elevation view from the back showing the back side of a preferred embodiment of our design.

FIG. 5 is an elevation view from the right showing the right side of a preferred embodiment of our design.

FIG. 6 is a plan view from the top showing the top side of a preferred embodiment of our design.

FIG. 7 is a plan view from the bottom showing the bottom side of a preferred embodiment of our design; and,

FIG. 8 is an isometric view from the front showing the front, bottom and left sides of a preferred embodiment of our design.

It should be understood that the descriptions used herein for describing orientation (e.g., front, back, top, bottom, right, and left) are merely for reference, and the design may be disposed in any manner and still be within the scope of the present invention.
